UNITED STATES PATENT OFFICE.

EDWIN A. RUTENBER, OF MARION, INDIANA, ASSIGNOR TO RUTENBER ELECTRIC CO.,
OF MARION, INDIANA, A CORPORATION.

ELECTRIC HEATING UNIT.

1,337,725.

Specification of Letters Patent. Patented Apr. 20, 1920.

Application filed April 22, 1918. Serial No. 230,024.

To all whom it may concern:

Be it known that I, EDWIN A. RUTENBER, a citizen of the United States, and a resident of Marion, county of Grant, and State 5 of Indiana, have invented a certain new and useful Electric Heating Unit; and I do hereby declare that the following is a full, clear, and exact description thereof, reference being had to the accompanying drawings, in which like numerals refer to like parts.

This invention relates to electric heaters and the prime object of the invention is the provision of a heating coil which is arranged within the reflector in such manner that the heat from the entire surface of the coil will be reflected. A further feature of the invention is the manner of attaching the heating coil to the reflector, and a further feature of the invention is the means for winding the heating coil upon an insulating core or support.

The full nature of the invention will be understood from the accompanying drawings and the following description and claim:

In the drawings, Figure 1 is a front elevation of the heater. Fig. 2 is a detailed sectional view thereof, as seen on the line 2—2 of Fig. 1. Fig. 3 is an enlarged detailed sectional view, as seen on line 3—3 of Fig. 2. Fig. 4 is an enlarged end elevation of the heating coil and its support.

Referring to the drawings, 1 indicates a pedestal which may be constructed in any preferred manner, and 2 indicates a reflector which also may be of the usual or any preferred type, the peripheral edge of said reflector preferably having a radial extension 3 attached thereto.

In heating devices of this class, it has been customary heretofore to place a heating coil transversely of the axial center of the reflector so that but a portion of the 45 heat from the coil will be reflected or thrown out into the room, but in the present device, the heating coil is wound upon an insulating core or support 5 preferably of porcelain or similar substance, said coil being entered in spirally arranged grooves 6 surrounding the core and extending from end to end thereof, the coil being wound from one end of the core in each alternate groove and then passed through a slot 7 in the 55 outer end of the core and rewound into the

remaining grooves until it is brought to the inner or initial end of the core. The core 5 and heating coil wound thereon are concentric with the axial center of the reflector 2 and the core is anchored in fixed position by extending a bolt 8 longitudinally through the core 5 through spacing blocks 9 and 10 and through a base block 11, all of which parts are likewise formed of insulating material, the spacing block 9 having a reduced portion 12 which passes through the opening in the reflector. Passing through openings in spacing blocks 9 and 10 and the base block 11 are wires 13, the outer ends of which are attached respectively to the ends of the coil and serve to conduct the electricity into the coil, the opposite ends of said wires being attached to binding posts 14 and to these posts are secured the usual form of feed wires 15 and as the binding posts 14 are also carried by the insulated base block 11, all of the current carrying parts are insulated from each other and from the parts of the reflector.

The various parts through which the bolt 8 extends are locked in fixed engagement with each other and with the reflector by introducing a nut 16 on the threaded end of the bolt 8 which jams against the face of the base block 11 while the head 17 of the bolt engages a shoulder 18 in a recess 19 at the outer end of the core 5 and when the nut is properly turned onto the bolt, all of the insulating parts will be held rigidly in place.

After these parts have been properly attached to the reflector, a shield 20 is introduced around the base block 11, the open edge of the shield resting against the rear face of the reflector 2, while the closed end thereof is provided with an opening through which the end of the bolt 8 extends, a nut 21 being employed for locking the shield onto the bolt. The feed wires 15 project through an insulated bushing 22 through the wall of the shield 20 which prevents said feed wires from coming in contact with any parts of the shield.

By mounting the heating coil in the manner shown and as the length of the heating coil is less than the depth of the reflector, all of the heat units from the entire surface of the heating coil will be projected outwardly by the reflector, thereby obtaining the maximum heating power from the coil.

It will likewise be seen that this device can be very cheaply constructed and quickly applied to use or removed from engagement with the reflector as it is but necessary to 5 release but the one bolt in order to remove and separate all of the parts of the heating unit.

The invention claimed is.

In a heating device, the combination with 10 a reflector having an opening at its axial center, of a heating coil, an elongated insulating core on which said coil is spirally wound, a spacing block for insulating the

heating coil from the reflector, a base block, and a bolt extending axially through said 15 core, spacing block and base block for locking them together and securing them in position.

In witness whereof I have hereunto affixed my signature in the presence of the 2° witnesses herein named.

EDWIN A. RUTENBER.
